COMBINED PUMP HANDLE AND LOCKING UNIT FOR FIRE EXTINGUISHERS

Charles K. Huthsing, Jr., Libertyville, Ill.; N. Evelyn Huthsing, executor of the estate of Charles K. Huthsing, Jr., deceased

Filed Aug. 11, 1970, Ser. No. 24,420

Term of patent 14 years

Int. Cl. D28—01

U.S. CL. D16—2 A

FIG. 1 is a perspective view of a combined pump handle and locking unit for fire extinguishers embodying my new design;

FIG. 2 is a front elevation thereof, the rear being the same as the front shown;

FIG. 3 is an elevation taken from one side thereof, the opposite side being the same as the side shown; and

FIG. 4 is a top plan view thereof.

I claim:

The ornamental design for a combined pump handle and locking unit for fire extinguishers, as shown and described.
